METHOD AND APPARATUS FOR TRANSLATING SOUND WAVE VARIATIONS

Filed Nov. 2, 1923

UNITED STATES PATENT OFFICE.

THEODORE WILLARD CASE, OF AUBURN, NEW YORK, ASSIGNOR TO CASE RESEARCH LABORATORY INCORPORATED, OF AUBURN, NEW YORK, A CORPORATION.

METHOD AND APPARATUS FOR TRANSLATING SOUND WAVE VARIATIONS.

Application filed November 2, 1923. Serial No. 672,324.

This invention relates to certain improvements in method and apparatus for translating sound wave variations into corresponding variations of an electric current, which latter variations may be used or translated as desired. Or perhaps differently stated, the invention relates to a method of apparatus for producing variations of an electric current in accordance with or corresponding to sound wave variations.

The main object of the invention is to produce a highly sensitive instrument that will intensify the sound effect and accurately translate sound waves into corresponding variations of electric current, which latter variations may be re-translated with or without amplification, and with practically perfect quality.

A further and more specific object resides in the elimination of distortion and foreign noises which might result from sympathetic diaphragm vibration, or other causes, and which effect the sound waves to be translated or their translation, and reference is hereby made to my co-pending application Serial No. 652,281 filed July 18th, 1923, upon gas-thermo microphone, and which describes and claims the broad subject matter disclosed herein, and to my application Serial No. 665,136 filed September 27th, 1923 upon microphone, and which latter application discloses the broad subject matter disclosed herein, and the claims of which are restricted to the adjustable opening within which the member that varies its resistance to the passage of an electric current in accordance with its temperature is positioned.

The specific subject matter described and claimed herein relates to the use of a specific gas, viz: hydrogen, which is highly efficient and peculiarly adapted for the purposes of this invention due to various characteristics, as for instance, its comparatively great cooling quality.

In the drawings:—

Figure 1 is a diagrammatic illustration of the invention with the gas chamber shown in section.

Figure 2 is a section on line 2—2, Figure 1.

Figure 3 is a front elevation of the gas chamber.

Figure 4 is a view similar to Figure 2, but in which the gas chamber has a circular

opening as distinguished from a somewhat rectangular one, and is taken on line 4—4, Figure 5.

Figure 5 is a horizontal section thru the gas chamber illustrated in Figure 4.

The invention, as shown, comprises a substantially flat disk —1— which may perhaps preferably be of circular form and is provided with an opening —2— illustrated in Figures 1, 2 and 3, as of substantially rectangular form; and in Figures 4 and 5 as of substantially circular form, altho the opening may be of various and many forms, and I do not, therefore, restrict myself to any shape, size or form of opening.

Within this opening is arranged a short wire —3— formed of a material that varies its electrical resistance in accordance with its temperature, and the opposite ends of this wire —3— are connected in circuit with the positive and negative sides respectively of a variable source of potential, such as the battery —4—, any suitable means of well known construction being provided for effecting desired variations of the source of potential utilized for heating the wire —3—.

Within this circuit may be positioned the primary —5— of a transformer, the secondary —6— of which may be connected to suitable amplifying means or directly to any suitable translating means, such as the telephone receivers —7—. Preferably the wire —3— is of very small diameter, as for illustration, plus or minus .00001, and is in the form of a coil or low pitch spiral, as indicated, and is arranged in the opening —2— in the disk —1—, and for illustrative purposes this opening —2— may be about one-half an inch long and one-quarter inch wide, and the wire —3— in its spiral form may be approximately one-quarter inch long so as to fit within the opening without contact therewith. However, the opening may be of various shapes, as circular, and the wire instead of being spiral in form, may be of varied forms, as straight, and more than one wire —3— may be used if desired.

The disk —1— may, as shown, be formed with an annular flange —8— penetrated by an inlet pipe —9— adapted to carry hydrogen gas under pressure from any suitable source of supply as blower —10— or the usual tank for containing such gases under pressure, and the rate of flow of hydrogen

from the pipe —9— is adjusted for the best sensitivity of the apparatus and may be just below the point where passage of the hydrogen through the opening —2— around the 5 wire —3— causes any noise as for instance, a hissing sound.

The sheet —11— of fabric, such as thin silk, may be secured across the open end of the flange —8— in any suitable manner, and 10 may be either taut or loose, so that in effect the rear of the gas chest is partially open and part of the hydrogen gas may escape therethrough. The remainder of the hydrogen gas entering the gas chest —12— 15 from the pipe —9— escapes through the opening —2— around the wire —3— and tends to cool the wire at all times. The wire may be formed of any suitable material that varies its resistance to the passage of 20 an electric current in accordance with its temperature, and altho various substances may be used, I have found platinum suitable for the purpose.

Placing the filament in an opening of desired size, such as the opening —2— intensifies the sound effect resultant from the use of the apparatus and without distortion. Preferably the disk —1— is used as the front of the apparatus, and is toward the speaker 30 or the sound waves which it is desired to translate, as in this position the sound waves to be translated are coming in a direction substantially opposite to the direction of the movement of the hydrogen gas escaping 35 through the opening —2—, and acting to cool the spiral wire —3—. This positioning of the instrument is not, however, essential, altho my present experience leads me to believe that a more advantageous result is 40 obtained in that manner.

I have found that it is very desirable and advantageous in an apparatus of this character to provide means for readily and easily varying the size of the opening —2— in 45 which the resistance element —3— is positioned; and in Figures 2 and 3 I have illustrated for this purpose slides or plates —13— and —14— positioned upon opposite sides of the opening —2—, and slidable 50 across the opening to restrict or enlarge its area as may be desired. These slides or shutters may be supported in any suitable way for adjustment, as described; and for that purpose I have shown them carried and 55 supported by studs —15— and —16— respectively which extend thru slots —17— and —18— respectively in the disk —1— for engagement with locking nuts —19— and —20— respectively for securing the slides in 60 any desired position of adjustment for producing the desired area of opening or gas passage.

These shutters —13— and —14—, as shown, are guided in channel-ways formed 65 by the undercut members —21—, —22—,

—23— and —24— secured to the disk —1— to permit sliding movement of the shutters when the nuts —19— and —20— are loosened, and to guide the shutters in their adjusting movement.

In Figures 4 and 5 the disk —1— is shown as provided with a circular opening —2— and the shutters —25— and —26— are each formed with semi-circular recesses so that when the shutters are adjusted in 70 one relative position they form a substantially circular opening, the size of which can be varied by sliding the shutters either toward or from each other, and for this purpose the adjacent ends of the shutters have 75 a portion of their thickness cut away so that one may slide upon the other. In other words, the inner ends of the shutters —25— and —26— are each preferably of substantially one-half the thickness of the body of 80 the shutter, as illustrated at —27— and —28—, and these parts are oppositely disposed so that one may slide upon the other, and jointly they constitute a thickness substantially equal to the thickness of the body 85 of either of the shutters —25— and —26—. Obviously, relative sliding movements of the plates —25— and —26— will vary somewhat the shape of the opening —2— 90 from an exact circular form and the structure I have shown is purely illustrative of a means for varying the size of an opening which at one particular adjustment is circular, and various and many other structures may be substituted for that shown, and well known constructions, such as a camera shutter may be utilized for adjusting the size of the opening —2—, the structures that I have shown being purely illustrative of means for accomplishing this desirable result of an adjustment of the hydrogen gas passage without limitation to the shape or size of the opening, as wide variation is possible in the shape, form and 100 size of the opening and the means for adjusting the area of the same within the scope of the appended claims. As before stated, this specific adjustment feature is the subject matter of the claims of a co-pending application.

It will be obvious that my invention so far as structure and arrangement of parts is concerned, may take various and many forms, and that so far as the subject matter here is concerned, I do not desire to restrict myself to any form, shape or construction of apparatus, as various changes may be made without departing from the invention as set forth in the appended claims.

I claim:

1. In an apparatus of the class described; the combination with a passageway for a forced current of hydrogen, and means for causing hydrogen under pressure to flow through said passageway of a member that 120

varies its electrical resistance in accordance with its temperature exposed to the hydrogen escaping through said passageway.

2. In an apparatus of the class described, means for producing a forced current of hydrogen, and a member which varies its electrical conductivity in accordance with its temperature exposed to the forced current of hydrogen and means for 10 heating said member.

3. In an apparatus of the class described, a chamber for hydrogen gas, means for supplying hydrogen gas under pressure to said chamber, an outlet from said chamber and 15 a member that varies its electrical conductivity in accordance with its temperature exposed to the hydrogen escaping through said outlet.

4. In an apparatus of the class described, 20 a chamber for hydrogen gas, means for supplying hydrogen gas under pressure to said chamber, an outlet from said chamber, a member that varies its electrical conductivity in accordance with its temperature ex-

posed to the hydrogen escaping through 25 said outlet, and means for heating said member.

5. In an apparatus of the class described, a hydrogen chamber, means for supplying hydrogen under pressure to said chamber, 30 an outlet from said chamber, a member that varies its electrical conductivity in accordance with its temperature arranged in said outlet, and means for heating said member.

6. In an apparatus of the class described, 35 a hydrogen chamber, means for supplying hydrogen under pressure to said chamber, an outlet from said chamber, a member that varies its electrical conductivity in accordance with its temperature arranged so as 40 to be exposed to the hydrogen which passes through said outlet in said outlet, and said chamber having a wall formed of a porous member.

In witness whereof I have hereunto set 45 my hand this 18th day of October 1923.

THEODORE WILLARD CASE.
